HOOD ORNAMENT

Grey J. Conrad, 2466 Ivanhoe, Pontiac, Mich. 48053

Filed July 8, 1966, Ser. No. 3,053

Term of patent 14 years

(Cl. D14—18)

FIG. 1

FIG. 4

FIG. 2

FIG. 3

FIG. 6

FIG. 1 is a perspective view of my novel, ornamental hood ornament in position on the hood of an automobile;

FIG. 2 is an enlarged perspective view of the hood ornament of FIG. 1;

FIG. 3 is a front view thereof;

FIG. 4 is a top view thereof;

FIG. 5 is a side view thereof, the other side view thereof being merely a mirror image of the figure; and

FIG. 6 is a rear view thereof.

The dominant features of my design reside in the portions shown in full lines, and the automobile fragmentarily shown in broken lines is included for illustrative purposes only.

I claim:

The ornamental design for a hood ornament, as shown and described.
